BY *John A. Gledhill*

ATTORNEY.

UNITED STATES PATENT OFFICE.

GEORGE W. BEAN, OF PHILADELPHIA, PENNSYLVANIA.

DESIGN FOR A BOTTLE-STOPPER.

SPECIFICATION forming part of Design No. 26,349, dated December 1, 1896.

Application filed February 29, 1896. Serial No. 581,399. Term of patent 7 years.

To all whom it may concern:

Be it known that I, GEORGE W. BEAN, a citizen of the United States, residing in the city and county of Philadelphia, State of Pennsylvania, have invented and produced a new and original Design for a Stopper and Sprinkler for a Perfumery or other Bottle, of which the following is a specification, reference being had to the accompanying drawings, forming part thereof.

The leading feature of my design for the stopper and sprinkler of a bottle is a tube of the form of a coil extended in the longitudinal direction thereof.

15 In the drawings, in which the figures rep-

resent side elevations in reversed positions of a bottle-stopper and sprinkler embodying my design, A designates a bottle-stopper and sprinkler consisting of an open-ended tube of serpentine form, or one which is deflected 20 in longitudinal direction, in the form of a coil, and which has an end adapted to fit in the neck of the bottle B, in which it is located.

What I claim is—

The design for a bottle-stopper and sprinkler, substantially as described and shown.

GEORGE W. BEAN.
